UNITED STATES PATENT OFFICE.

JOHN B. HUNZELMAN, OF SOMERVILLE, MASSACHUSETTS, ASSIGNOR TO WM. F. SCHRAFFT & SONS CORP., OF BOSTON, MASSACHUSETTS, A CORPORATION OF MASSACHUSETTS.

SHIPPING CASE.

Application filed June 26, 1925. Serial No. 39,839.

This invention relates to shipping cases. Certain commodities are disposed in small boxes or packages, a number of which are packed together in a large rectangular case for shipment. Some commodities, as, for instance, certain confections, are found to be more or less damaged upon arrival at their destination, even though great care is exercised in packing the confections and in providing strong shipping cases. Investigation has disclosed the fact that damage is incurred, not while the cases are being transported by car or truck, as might ordinarily be expected, but when the cases are loaded into or unloaded from the conveying vehicle.

The shipping cases are usually rectangular and have flat sides and ends. When a case is unloaded from an express car onto a platform, for instance, it is customary for a mover to place the case end-up on the commonly used two-wheeled truck, wheel the case to the desired location and then to up-tilt the truck to remove the case. By this action, the case is caused to rock about an end and to fall to the floor upon one of its side faces and, usually, its broadest face. The case, and its contents, acquire a considerable speed just prior to striking the platform or floor, and the sudden, and violent, arresting of movement of the case causes the delicate contents of the case to become damaged or crushed by their own inertia.

This invention relates to means to prevent damage to the contents of the case by such treatment and has for one of its objects to provide a shipping case with means to prevent the sudden shock to its contents incident to the up-tilting and falling of the case.

A further object is the provision of a shipping case having means gradually to stop the motion of the case due to its up-tilting.

A further object is generally to improve the construction of shipping cases.

Fig. 1 is a perspective view of a shipping case embodying the invention.

Fig. 2 is a sectional detail of the method of attaching a rocker removably to the case.

Fig. 3 is an end view of a stack of shipping cases embodying this invention and illustrating more particularly the manner of off-setting the rockers to permit compact stacking of the cases.

Fig. 4 is a view illustrating the action of the rockers.

Fig. 5 is a view similar to Fig. 1 but showing a rocker applied to each face of the shipping case. The shipping case embodying this invention is here shown as of rectangular form and composed of the flat end faces 10, the narrow and flat side faces 12, and the broad and flat side faces 14, although the invention is not necessarily limited to a case having such relative dimensions. The case is mechanically strong and usually will be composed of wood.

In accordance with this invention the case is provided with means to prevent it from having its falling movement suddenly arrested, and the specific means comprises rockers 16, which are made of any suitable material, as wood, and are applied to such faces of any particular type of case as may be found desirable. For the specific type of case illustrated, the rockers are applied to the broad faces thereof as it has been found that usually this type of case is so handled as to be caused to fall upon one of its broad faces. Said rockers preferably are approximately co-extensive with the length of the case and are disposed thereon approximately parallel with the side edges. Said rockers are formed with flat faces 18, which are disposed against the flat sides of the cases, and with convex case-supporting outer faces 20 on which the cases are adapted to rock in falling and by which the case is gradually brought to rest without shock. Preferably the highest parts of the rockers are in the middle thereof and the rockers taper gradually and uniformly to the ends 22, whereat the rockers are thin. The rockers are secured to the cases, preferably removably, by any suitable means as screws 24 which extend through the ends of the rockers and into the ends of the cases.

The rockers are applied to the opposite broad faces of a case, preferably in pairs, although a single rocker on a face is effective. The pairs of rockers on the opposite sides of the case are staggered or off-set with respect to each other so that, when a plurality of cases thus arranged are superimposed in piles, the rockers of adjacent cases will nest one beside the other, as illustrated in Fig. 3.

When a case provided with rockers as above described is discharged from a truck as illustrated at a, Fig. 4, so that it will tilt

about its lower edge 3 in falling, the ends of the rockers are first brought into contact with the floor or platform. Due to the convexity of the rockers, the points of contact 5 shift from one end to the other of the rockers and the direct falling movement of the case is transformed into a rocking or oscillatory movement on the rockers, until the case gradually comes to rest without 10 shock and damage to its contents.

Fig. 5 illustrates a shipping case provided with rockers on all flat faces thereof whereby protection is afforded to the contents of the case regardless of the manner in 15 which the case is manipulated.

I claim:

1. A rectangular shipping case having flat side and end walls and straight edges and having at least one of its long side walls 20 formed with a flat internal face and an outer supporting-face which is convex along its length only and is co-extensive with the length of the side wall between two of the straight edges.
- 25 2. A rectangular shipping case having opposed long side walls that have flat internal faces and convex outer supporting-faces which are convex in the direction of the length and are co-extensive with the length 30 of the side walls.
3. A shipping case having flat internal faces and flat sides and straight edges and having a pair of spaced rockers fixed to and carried externally by at least one side there- 35 of and extended substantially co-extensive and parallel with the length of said side and terminated at opposed straight edges.
4. A shipping case having flat sides and

having rockers carried on two of the opposed side faces of the cases, said rockers 40 being disposed substantially parallel and co-extensive with the length of said faces, and with each other, the rockers on one face being staggered with respect to the rockers on the other face. 45

5. A shipping case having flat sides and having a pair of spaced rockers on each of two of its opposed side faces, each pair of rockers being substantially parallel with the length of said faces, and said pairs of 50 rockers being staggered with respect to each other.

6. A shipping case having flat sides and straight edges and a pair of parallel spaced rockers carried by one of said sides, each 55 rocker having a flat face which is disposed against and is fixed to the flat side of said case and also having a convex case-supporting outer face, the rocker being thin at the ends and thick at the middle and extended 60 parallel to the long dimension of the side with the thin edges terminated at opposite straight edges of the case.

7. A rectangular shipping case having flat sides and ends and a rocker extended across 65 and extended above one of said flat sides, said rocker being curved from end to end and arranged to arrest the fall of the case gradually when the case is tilted about that edge of the case adjacent one end of the 70 rocker, whereby to reduce the shock of falling on the fragile contents of the case.

In testimony whereof, I have signed my name to this specification.

JOHN B. HUNZELMAN.
